UNITED STATES PATENT OFFICE.

SANFORD A. MOSS, OF LYNN, MASSACHUSETTS, ASSIGNOR TO GENERAL ELECTRIC COMPANY, A CORPORATION OF NEW YORK.

CENTRIFUGAL COMPRESSOR.

1,041,505.

Specification of Letters Patent. Patented Oct. 15, 1912.

Application filed March 5, 1908. Serial No. 419,278.

To all whom it may concern:

Be it known that I, SANFORD A. Moss, a citizen of the United States, residing at Lynn, county of Essex, State of Massachusetts, have invented certain new and useful Improvements in Centrifugal Compressors, of which the following is a specification.

When the ordinary reciprocating compressor is employed to supply air to a blast furnace or cupola and a choke occurs somewhere in the air passages which reduces the air openings, the pressure automatically increases or builds up until the choke is removed. This is due to the fact that the piston of the compressor displaces a given volume of air on each stroke and is moving at constant speed. The centrifugal compressor has many important advantages over the reciprocating compressor for such work but it has this objection, namely, that if driven at constant speed by a suitable prime mover it will give practically constant pressure under all circumstances. In other words, if the cupola chokes up, the compressor will supply less air but at the same constant pressure, whereas as above pointed out, an increased pressure is necessary to overcome the choke or obstruction.

My invention has for its object the overcoming of the objection above referred to by so arranging, constructing and operating the apparatus that just as soon as the amount of air delivered by the centrifugal compressor and consequently the load on the prime mover driving said compressor decreases owing to a choke in the cupola or other apparatus, the speed of the compressor and of its driving motor will, because of the unchanged or constant supply of energy to the driving motor, automatically increase until the air pressure is increased sufficiently due to said increase in speed to overcome the choke or obstruction, after which the pressure and speed will decrease and return to their normal conditions. Should a predetermined increase of pressure fail to remove the choke, provision is made for preventing further increase in speed above a desired maximum by controlling the supply

of energy to the driving motor by means that is ordinarily inactive but becomes effective at said maximum speed.

In carrying out my invention, a centrifugal compressor is provided, which, if operated or driven by a prime mover of constant speed would give practically constant pressure at said speed for all loads, that is for all quantities of fluid discharged by the compressor. The compressor illustrated is designed to supply 7000 cubic feet of free air per second at a pressure of .88 pounds per square inch under normal conditions. The quantity and pressure of the air or other elastic fluid delivered can be changed to meet different normal conditions by suitably changing the parts and driving the impeller of the compressor at the proper speed.

Mounted on the same shaft with the impeller of the compressor, or on a different shaft and connected thereto, is the moving element of a driving motor. As an illustration of a motor I have shown a steam turbine since it is particularly well adapted for the purpose on account of its simplicity, economy of operation and relatively high speed, but the invention is not necessarily limited thereto in all particulars. The turbine is provided with one or more nozzles or other fluid discharging devices to admit the required amount of steam to drive the bucket wheel and the impeller at such speed as will cause the latter under normal conditions to deliver the desired quantity of air at the predetermined pressure. The turbine is provided with a governor which under normal conditions of operation and for a certain range of speed above normal is inactive, that is, it has no effect on the steam supply which remains constant under such circumstances, but when the speed has increased a certain amount above normal, due to the decrease in the load on the turbine, said governor comes into service and reduces the steam supply. The action of the turbine with the governor inoperative will be to give substantially constant power regardless of speed. The compressor when supplied with constant power will give a pressure substantially inversely proportional

to the volume. Hence when the volume decreases the pressure increases. To state the matter in another way, if the cupola chokes, the load on the compressor or in other words, the quantity of air delivered by the compressor, decreases while the speed of its impeller increases because the input of energy in the form of steam supplied to the turbine remains the same and the load on the turbine is less. Hence the pressure of the discharged air will be increased due to the increased speed of the impeller. This increase of speed ordinarily continues until the increasing pressure of the air overcomes the resistance to its passage. If, however, the resistance is not overcome when a predetermined pressure is produced the governor will become active at some corresponding predetermined abnormal speed and prevent further increase of speed and pressure.

The governor may be made to act in the manner above described in a variety of ways. As an example, one or more stops may be provided which hold the weights out away from the shaft axis and in such a position that they are inoperative, in so far as their effect on the controlling valve is concerned, until the speed of the bucket wheel exceeds the predetermined limit after which they move the controlling valve toward its seat in the usual way until a balance is again effected between the steam input and the output of compressed air. This relation continues until the choke in the cupola is removed and the normal amount of air is discharged by the compressor, when the governor weights return to their usual position against the stop or stops. It will be seen that the governor has no control so long as the speed does not rise above said predetermined value, the full steam admission satisfying the ordinary operating requirements of the compressor, but it has control when the conditions beyond the compressor become abnormal to the extent described.

A main valve may be provided in the steam supply pipe of the turbine to reduce the initial pressure whereby the normal operating conditions of the apparatus may be changed and this without modifying the construction or relation of the parts.

In the accompanying drawings which illustrate one of the embodiments of my invention, Figure 1 shows a turbine-driven centrifugal compressor connected to a cupola; and Fig. 2 is a view of the turbine with certain parts broken away.

1 indicates a centrifugal compressor which is designed to give practically constant pressure for a given speed at all loads or quantities of air delivered and is operated at different speeds and pressures under the conditions above described. It is provided with an inlet 2 through which air is sup-

plied to the interior of the compressor casing from any desirable source and with an outlet 3 which is connected by a conduit 4 with a cupola or other apparatus 5 designed to receive air. Mounted on the main shaft 6 is an impeller 7 of any suitable construction which in the form illustrated in the drawing receives through the openings 7^a adjacent the shaft 6 air delivered to the interior of the casing by the inlet 2. Surrounding the impeller is an annulus 8 containing vanes 9 which convert the velocity of the air discharged by the impeller into pressure before discharging it into the outlet. The shaft is supported by bearings 10 and 11 of suitable construction. Mounted on one end of the main shaft for driving it is a turbine bucket wheel 12, Fig. 2. The turbine is provided with a casing 13 that is supported by a part of the adjacent pillow-block. The bucket wheel is provided with rows of buckets 14 between which are rows of intermediate buckets 14'. Steam is admitted to the buckets by a nozzle 15 having one, two or more sections or passages through which the steam flows. Bolted to the face of the turbine casing is a valve chest 16 containing a regulating valve 17, the latter being ordinarily wide open and supplying steam to all of the passages in the nozzle 15 or other device for discharging fluid to the wheel buckets. Situated in front of the valve chest 16 is a second valve chest 18 containing an emergency valve 19 which shuts off the steam supply in case of an emergency such as an excessive and dangerous increase of speed due to the failure of the main governor to operate. This valve 19 may be actuated by any well known form of emergency governing device which is brought into active operation by a certain speed greater than that normally permitted by the main governor. Steam is admitted to the chest 18 by a conduit 20 containing a manually operated throttle valve 21. On the end of the main shaft 6 is a centrifugal governor comprising weight-arms 22 whose movements are opposed by the coiled extension spring 23. The tension on this spring is such that it prevents the governor weights 30 from acting so long as the speed of the motor is normal or below normal and the quantity and pressure of the air delivered by the compressor are normal. Said spring also opposes the action of the weights during the increase in speed and pressure permitted when a choke occurs but its opposition is overcome by the centrifugal action of the weights when said speed and pressure reach the predetermined limit. The governor then holds the speed substantially constant at that limit. One end of the spring 23 is threaded to a fixed nut that surrounds said end while the opposite end is secured to a movable abutment 24. This abutment is 125

connected by a rod 25 with one end of a bell-crank lever 26 that is pivotally mounted within the casing 27. The other end of the lever is connected to the stem 28 of the valve 17. Located at any suitable point, as for example, on the outside of the shell surrounding the spring and in line with the weights 30, are stops 29 which limit the inward movement of the weights. These 10 governor weights are in engagement with the stops for all speeds below that for which the governor is set, so that the valve 17 remains wide open, this being the ordinary running position of the parts.

Assuming that an obstruction occurs in the cupola or other apparatus receiving air from the compressor, the amount of air delivered by the compressor will decrease and since the valve and nozzle openings remain 20 the same, the speed of the turbine and hence that of the impeller will increase with a resulting increase in the pressure of the air delivered by the compressor. This increase continues until the pressure is sufficient to 25 overcome the choke or obstruction in the cupola when the load on the compressor returns to normal, accompanied by a decrease in the speed of the turbine. Assuming, however, that the choke or obstruction in the 30 cupola is not readily overcome, the speed of the turbine will increase to a point where the governor becomes effective and prevents said speed becoming abnormally great by decreasing the admission of steam. It will 35 be seen that under ordinary conditions the turbine is running with full steam admission and for all practical purposes without the governor, the speed and pressure varying somewhat with the load, that is, with the 40 quantity of air discharged by the compressor. This action continues until the counter pressure and speed rise to a predetermined amount when the governor comes into service and maintains a constant speed and discharge pressure of the compressor.

In accordance with the provisions of the patent statutes, I have described the principle of operation of my invention, together with the apparatus which I now consider to 50 represent the best embodiment thereof; but I desire to have it understood that the apparatus shown is only illustrative and that the invention can be carried out by other means.

What I claim as new and desire to secure 55 by Letters Patent of the United States, is,—

1. In combination, a centrifugal compressor which delivers fluid at substantially constant pressure when driven at constant speed under normal delivery conditions, a fluid-actuated motor for driving the compressor, a regulating valve for the motor that is open to a fixed extent during the ordinary operation of the compressor and supplies a constant quantity of motive fluid to drive the 60 compressor at a constant speed under nor-

mal delivery conditions and at an increasing speed from normal speed up to a predetermined limit above normal if the delivery of the compressor is choked, and a governor having a member that tends to hold the 70 valve open and means responsive to said predetermined speed that overcomes the action of said member and closes the valve to a greater or less extent when the speed tends to exceed said limit.

2. In combination, a centrifugal air compressor which delivers air at approximately constant pressure and volume so long as its outlet is unobstructed, a motor which is ungoverned during the ordinary operation of 80 the compressor and is direct-connected to said compressor, means delivering a substantially constant supply of energy to the motor so that its speed increases as the load decreases below normal, and a speed governor which is ordinarily inactive and only comes into service to limit the speed of the motor by controlling the input of energy when the volume of fluid delivered by the 85 compressor decreases below a predetermined 90 amount and its pressure increases to a predetermined limit due to an obstruction in the compressor outlet.

3. In combination, a motor which is connected to a centrifugal air compressor which delivers air at approximately constant pressure at constant speed and at higher pressures at higher speeds, means furnishing a constant supply of energy to the motor during the ordinary operation of the compressor and up to a predetermined increase in speed and delivery pressure, and a speed governor which is ordinarily inactive but becomes active at said predetermined speed 100 to regulate the supply of energy to the motor and prevent a further increase in speed and delivery pressure.

4. In combination, a centrifugal compressor, a fluid-actuated motor for driving it, a valve controlling the supply of fluid to the 110 motor, and means for holding the valve open to a fixed extent while the load is normal and during the decrease of the load to a certain point, said means including speed responsive mechanism that becomes active at 115 a speed corresponding to said point of decreased load and closes the valve to a greater or less extent.

5. In combination, a motor for driving a centrifugal air compressor, means furnishing a substantially constant supply of energy to the motor during the ordinary operation of the compressor so that its speed increases above normal as the load decreases below normal, and a speed responsive mechanism which is ordinarily inactive but becomes active at a predetermined increase in speed above normal to regulate the supply of energy to the motor to prevent a further increase in speed.

6. The method of operating motor-driven centrifugal compressors which consists in furnishing a substantially constant supply of energy to the motor during the ordinary operation of the compressor at normal load and also as the load decreases so that the speed can increase with a decrease in load, and regulating the supply of energy to the motor when the speed increases to a pre-

determined limit so as to prevent a further 10 increase in speed.

In witness whereof, I have hereunto set my hand this second day of March, 1908.
